UNITED STATES PATENT OFFICE

HERBERT OBLANDER, OF CHICAGO, ILLINOIS, ASSIGNOR TO BUNTE BROTHERS, OF CHICAGO, ILLINOIS, A CORPORATION OF ILLINOIS

DESIGN FOR A BOTTLE OR SIMILAR CONTAINER

Application filed September 8, 1930. Serial No. 36,899. Term of patent 14 years.

To all whom it may concern:

Be it known that I, HERBERT OBLANDER, a citizen of the United States, residing at Chicago, Cook County, Illinois, have invented a new, original, and ornamental Design for a Bottle or Similar Container, of which the following is a specification, reference being had to the accompanying drawing, forming part thereof, showing my new design.

I claim:

The ornamental design for a bottle or similar container as shown.

HERBERT OBLANDER.
